FOLDING BOX.

(Application filed Dec. 20, 1900.)

(No Model.)

2 Sheets—Sheet 2.

This technical drawing illustrates a rectangular frame structure, likely a component of a larger assembly. The frame is defined by a thick, hatched border. The interior is divided into several sections by horizontal and vertical lines. Key labeled components include:

- Top edge: 12, 13, 11, 16
- Left edge: 48, 50, 45, 40, 22, 54, 12, 20, 11
- Right edge: 49, 48, 50, 54, 38, 12, 21, 53, 11
- Bottom edge: 10, 16
- Internal features: 39, 44, 15, 20, 53

UNITED STATES PATENT OFFICE.

HARRY B. MARLIN AND JOSEPH L. BECK, OF HUNTINGDON, PENNSYLVANIA.

FOLDING BOX.

SPECIFICATION forming part of Letters Patent No. 674,587, dated May 21, 1901.

Application filed December 20, 1900. Serial No. 40,549. (No model.)

To all whom it may concern:

Be it known that we, HARRY B. MARLIN and JOSEPH L. BECK, citizens of the United States, residing at Huntingdon, in the county of Huntingdon and State of Pennsylvania, have 5 invented a new and useful Folding Box, of which the following is a specification.

This invention relates to folding boxes; and it has for one object to provide a simple and 10 cheap construction of box which when set up will be held rigidly against collapse.

A further object of the invention is to provide a construction wherein the sides and 15 ends will fold to lie in close relation and wherein the top may be slidably engaged with the body portion in both the set-up and knock-down positions of the body and will be held against displacement and will in turn hold the 20 elements of the body in their set-up or unfolded positions and their knocked down or folded positions.

Further objects and advantages of the invention will be evident from the following description.

25 In the drawings forming a portion of this specification and in which like numerals of reference indicate similar parts in the several views, Figure 1 is a perspective view showing the box set up. Fig. 2 is a plan view of the 30 box with cover removed and one of the sides folded part way inwardly. Fig. 3 is a section on line 3 3 of Fig. 1. Fig. 4 is a section on line 4 4 of Fig. 1. Fig. 5 is a perspective view showing the box folded. Fig. 6 is a section on line 6 6 of Fig. 5. Fig. 7 is a section on 35 line 7 7 of Fig. 5. Fig. 8 is a detail view, partly in section, showing a portion of the box with the means for holding the end of the cover in place.

40 Referring now to the drawings, the present box comprises a bottom 10, having supplemental side pieces 11, 12, 13, and 14 fixed to its edges and projecting thereabove to equal extents, and within the inclosure of these 45 supplemental sides the main sides are hinged and into which they are adapted to fold to lie below the upper edges of the supplemental sides. One of the main side pieces 15 is hinged with its lower edge in the corner between the bottom 10 and the supplemental side 11 and is adapted to lie against the bottom 10 or to stand erect against the inner face

of the supplemental side piece 11. The hinge employed is a long pintle-rod 16, which is held to the lower edge of the side 15 by straps 55 17, additional straps 18 being also passed over this pintle-rod and secured to the bottom and the supplemental side 11. The pintle is held from displacement by the supplemental sides, at the ends thereof, and by reason of the loose engagement of both sets of straps with the pintle binding of the parts is prevented. A strip 19 is secured in the corner between the bottom 10 and the supplemental side 12 and is of a height substantially 60 equal to the thickness of the side piece 15, and on the upper edge of this strip is disposed a pintle-rod 20, held by straps 21. A main side piece 22 is disposed with its bottom edge against the pintle-rod 20 and is held 65 by straps 23, engaged loosely with the rod, so that the side 22 may be folded to lie upon the side 15. A third strip 25 is disposed between the bottom and the supplemental side 13, and to the upper edge of this strip is hinged a 70 main side 26 by means of the long pintle-rod 27 and the straps 28 and 29, this side 26 being adapted to fold to lie upon the side 22. A fourth strip 30, disposed in the angle between the bottom and the side piece 14, has 75 the fourth side 31 hinged thereto by means of the pintle-rod 32 and the straps 33 and 34.

Secured to the inner faces of the sides 15 and 22 are plates 35 and 36, respectively, which are bent around the corners of the sides to lie 80 parallel with and spaced from the side edges of the said sides and projecting outwardly of the box when the sides are in their unfolded positions. Additional plates 37 and 38 are secured to the inner faces of the sides 26 and 31 and are bent upon themselves to form 85 hook-plates, as shown, the bills of the hooks on each side 26 and 31 projecting toward each other. When the sides 26 and 31 are in their raised or unfolded positions, they are so 90 spaced that when the sides 15 and 22 are subsequently raised the latter will rub with their plates 35 and 36 against or in close relation to the inner faces of the upright sides, and the outwardly-bent portions of the plates 35 95 and 36 will engage with the hooks of the plates 37 and 38 to hold the sides in their erect positions.

At the upper edges of the sides 15 and 22

there are secured additional plates 39 and 40 to the inner faces of said sides and bent with their upper edges or portions over the upper edges of the sides 15 and 22 and spaced therefrom, and these outwardly-projecting portions, which are bent over the upper edges of the sides 15 and 22, are adapted for engagement slidably by the hook-plates 41 and 42, which are secured against the under side of the top portion 43 of the cover of the box. Angle-plates 44 and 45 are secured to the under face of the top of the cover and spaced with their depending portions inwardly from the hook-plates to lie against the inner faces of the sides 15 and 22 and prevent inward folding of the said sides when the cover is in place. To permit inward movement of the cover to its place, slots 46 are cut in the upper edges of the sides 26 and 31, which receive the depending portions of these angle-plates 44 and 45.

The cover of the box includes not only the top board or piece 43, but also the fixed side pieces or depending flanges 46', 47, and 48. To the inner faces of the flanges 46 and 48 are secured plates 49 and 50, which are bent outwardly under the flanges and spaced therefrom, and when the sides of the box are folded to lie within the inclosure of the supplemental side pieces these plates 49 and 50 are adapted to be slidably engaged with similar plates 53 and 54, which are secured to the supplemental side pieces 11 and 12 and bent outwardly over the upper edges thereof, the flange 47 preventing dislodgment slidably of the cover in one direction when in one of its positions—that is, when engaged with the main sides of the box. Displacement of the cover slidably in the opposite direction is prevented by a fourth flange 55, which is removably secured, so that it may be removed when the cover is to be removed from the box or when it is to be applied. To hold the flange 55 in place, it has the duplicate hook-plates 56 and 57 secured to its inner face, adjacent to the ends thereof, and which are adapted for slidable engagement with the duplicate plates 58 and 59, which are secured to the inner faces of the flanges 46 and 48 and bent outwardly across the free ends thereof. An additional hook-plate 60 is attached to the inner face of flange 55 at the upper edge or adjacent to the upper edge and is adapted to engage the upturned edge of plate 61, which lies in a recess in the end of the top of the box-cover, said plate 61 being attached to the under side of the top of the cover. This flange 55 is placed and removed by a movement in a plane at right angles to the plane of the top of the cover, and when it is in place and the cover is on the box it lies with its inner face against the outer face of the side 31.

When the cover is applied with the box in its folded condition, the cover is prevented from slidable displacement by plates 62 and 63, which are secured against the outer faces of the flanges 47 and 55 and depend therefrom

to lie against the supplemental side pieces 13 and 14. Thus in either of its positions the cover can only be removed by first sliding the flange 55 from its place, and to prevent accidental displacement of this flange a latch is provided. This latch consists of a spring-wire 65, which is attached midway of its ends to the outer face of flange 55 and has its end portions bent at right angles and engaged through perforations 66 in the flange and adapted to lockingly engage with perforations or recesses 67, formed in the end of the top of the cover.

With this construction it will be seen that there is provided a construction wherein the parts may be readily adjusted to their folded or their unfolded positions and that when so adjusted and having the cover in place they are held securely against displacement, and it will be understood that by applying a simple form of locking device to the removable flange 55 the box may be securely locked in either position.

In practice various modifications of the specific construction shown may be made, and any suitable materials and proportions may be used for the various parts without departing from the spirit of the invention.

What is claimed is—

1. A folding box comprising a bottom, oppositely-disposed sides hinged to fold inwardly over the bottom, additional oppositely-disposed sides hinged to fold over the bottom and to stand erect thereon between the first-named sides to prevent folding of the latter, hook-plates at the upper edges of the second sides, and a cover adapted for slidable engagement with the hook-plates to prevent folding of the sides by which they are carried when the cover is in place, said cover having flanges to lie against the outer faces of the sides and one of the flanges being movable to permit of application and removal of the cover to prevent folding thereof when the cover is in place.

2. A folding box comprising a bottom, sides hinged to fold over the bottom and disposed mutually opposite said sides having hook-plates at their side edges, additional sides hinged between the first-named sides to fold over the bottom and to stand erect between the first-named sides, the second sides having plates lying parallel with and spaced from the side edges thereof for engagement with the hook-plates when said sides are unfolded, to hold all sides against outward displacement, and having hook-plates at their upper edges, and a cover adapted for slidable engagement with the hook-plates at the upper edges of said sides to prevent folding thereof when the cover is in place.

3. A folding box comprising a bottom, sides hinged to fold over the bottom and adapted to stand erect with one pair of sides between another pair to prevent displacement thereof, hook-plates at the upper edges of the inner pair of sides, a cover having hook-plates for

slidable engagement with the hook-plates of the innermost sides to prevent inward folding thereof, and means for holding the cover in place.

5 4. A folding box comprising a bottom, sides hinged to fold over the bottom, additional sides hinged to fold over the bottom and to stand erect between the first-named sides to prevent folding thereof, and a cover for slid-
10 able engagement with the second-named sides to prevent inward folding thereof, said cover having flanges disposed to lie against the outer faces of the sides and one of the flanges being removable to permit of application and
15 removal of the cover.

5. A folding box comprising a bottom, sides hinged to fold over the bottom, additional sides hinged to fold over the bottom and adapted to stand between the first-named sides to prevent inward folding thereof, and a cover slidably engaged with the last-named or second sides to prevent inward folding thereof and having flanges for engagement with the outer faces of the first-named sides to pre-
20 vent displacement of the cover.

6. A folding box including a bottom, sides connected with the bottom and adapted to fold to lie thereover, additional sides connected with the bottom between the first-named sides
30 and adapted to fold to lie over the bottom and to stand between the first-named sides to prevent inward folding thereof, and a cover comprising a top having flanges adapted for engagement with the second-named sides to hold them against inward folding, said top having a fixed flange adapted for engagement with one of the first-named sides to prevent displacement in one direction and having a flange removably engaged therewith to lie
35 against the opposite first-named side to prevent displacement in the opposite direction.

7. A folding box including a bottom, sides disposed to fold against the bottom and to stand erect, additional sides adapted to fold
40 against the bottom and stand erect between the first-named sides to prevent inward displacement thereof, a cover for slidable en-
gagement with the second sides to prevent in-

ward displacement thereof, and flanges upon the cover adapted to lie against the outer 50 faces of the sides for preventing outward displacement of the sides, one of the flanges being slidably engaged with the cover for movement therefrom to permit of application and removal of the cover.

55

8. A folding box comprising a bottom having supplemental sides, additional sides disposed within the inclosure of the supplemental sides and adapted to fold over the bottom and to stand erect alternately, and a cover 60 adapted for engagement with the supplemental sides when the box is folded and for engagement with the main sides when the box is unfolded, said cover having flanges at its edges to lie against the sides of the box, one 65 of the flanges being slidably engaged with the cover for movement therefrom to permit of application and removal of the cover and having a latch for engagement with the cover to hold it in place.

70

9. A folding box comprising a bottom having sides connected therewith and adapted to fold to lie thereover, additional sides connected with the bottom and adapted to fold thereover and to stand between the first sides, 75 hook-plates at the upper edges of the last-named sides, supplemental sides connected with the bottom and adapted to receive the main sides therebetween when folded, hook-plates upon the supplemental sides adjacent 80 to the main sides having the hook-plates at their edges, and a flanged cover having hook-plates adapted for engagement with the hook-plates of the second sides to hold them against folding and having hook-plates adapted for 85 engagement with the hook-plates on the supplemental sides to hold the cover thereon when the sides are all folded.

In testimony that we claim the foregoing as our own we have hereto affixed our signatures in the presence of two witnesses.
